MACHINE FOR PERFORMING SUCCESSIVE
OPERATIONS ON MATERIALS

Julius J. Miller, St. Joseph, Mich.

Application May 11, 1938, Serial No. 207,203

24 Claims. (CL. 1—8.2)

This invention relates to machinery for making wirebound box blanks, or similar blanks, and more particularly to machines of this kind that are provided with a plurality of staplers that drive the necessary staples in the blanks, as the latter move along toward the end of the machine from which the finished blanks are discharged.

Generally stated, the object of the invention is to provide a novel and improved construction and arrangement for predetermining the points of insertion of the staples on the blanks, thereby to avoid the insertion of staples at points where such insertion would not be desirable, and to do this in a manner obviating the necessity of using certain expedients heretofore considered necessary for this purpose, and tending to insure more satisfactory results than heretofore.

More specifically considered, the object of the invention is to provide a novel and improved construction whereby the positioning of the staples on the blanks is automatically controlled by moving the staplers, which latter travel a distance with the blanks, either forward or backward, longitudinally of the machine, while the blanks are moving continuously forward under the staplers, thereby insuring the desired positioning of the staples on the blanks, in accordance with the size and shape and character of the latter, but without changing or varying the timing of the vertical stroke of the staple drivers.

It is also an object to provide certain details and novel features of construction and combinations tending to increase the general efficiency and desirability of a box blank machine of this particular character.

To the foregoing and other useful ends, the invention consists in matters hereinafter set forth and claimed and shown in the accompanying drawings, in which—

Fig. 1 is a side elevation of a box blank machine embodying the principles of the invention.

Fig. 2 is a vertical transverse section on line 2—2 in Fig. 1 of the drawings.

Fig. 3 is a detail vertical section on line 3—3 in Fig. 2 of the drawings.

Fig. 4 is a perspective of certain portions of the said machine, including the side frame and the staplers, with the automatic control shown at the extreme left.

Fig. 5 is a detail sectional plan view on line 5—5 in Fig. 4 of the drawings, showing one of the rack and pinion devices for automatically adjusting the staplers.

Fig. 6 is a perspective view of certain portions of the said machine, showing the automatic con-

trol for preventing the driving of staples in the spaces between blanks.

Fig. 7 is a detail view, on a larger scale, of the ratchet device shown at the left in Fig. 6 of the drawings, for feeding the staple wire.

Fig. 8 is a detail vertical section on line 8—8 in Fig. 7 of the drawings, showing said ratchet device.

Fig. 9 is a plan view in diagram of the cam groove of the automatic controlling mechanism 10 by which the positioning of the staples on the blanks is controlled.

Fig. 10 is an edge view of one of the blanks.

Fig. 11 is an enlarged detail sectional view on line 11—11 in Fig. 1 of the drawings, showing the automatic control.

Fig. 12 is a side elevation of certain portions shown in Fig. 11 of the drawings, showing the endless link belt of said automatic control.

Fig. 13 is a perspective view of certain portions of the machine, illustrating the feeding and guiding means for causing the blanks to move continuously forward under the staplers.

Figs. 14, 15 and 16 are diagrammatic views illustrating the different positions assumed by the staplers, while actually driving the staples, as a result of the automatic control exercised over these staplers by the automatic control devices provided on the machine.

Fig. 17 is a perspective of a box made from one of the blanks made on the machine shown and described.

As thus illustrated, Figs. 1 and 2, the invention comprises a machine body or frame 1, suitably supported on base portions 2 and 3 that rest on the floor of the plant or shop in which the machine is used. This body frame preferably comprises two side members, in the form of castings, that are connected together in any suitable manner, as by a bar 4, at their tops, so that they are held parallel.

At the opposite ends of the body frame, supported in suitable bearings, there are transverse shafts 5 and 6 disposed in the same horizontal plane and provided with suitable sprockets on which the feed belts 7 are mounted or supported, which belts feed the blanks in any suitable or desired or known manner, side guides 8 being provided to prevent lateral displacement of the blanks. These feed belts, which are common and well known, serve to positively feed the cleats 9 and the sheets 10 of the blanks continuously toward the discharge end of the machine.

The two side frames are connected together by the main transverse shaft 11, which latter is con-

nected by a chain belt 12 with the gearing 13, which latter is connected by a chain belt 14 with the shaft 5, so that the latter is driven continuously at the desired rate of speed for feeding the blanks along the horizontal path of travel thus provided for them on the body frame of the machine. The shaft 11 is driven by a chain belt 15 from the shaft 16, which latter is transversely mounted in bearings on the body frame, parallel with the shaft 11, and the shaft 16 is driven by an ordinary belt 17, or from any source of power. In this way, the feed belts 7 for feeding the blanks are given a continuous feeding motion by power communicated to them from the shaft 11, so that the blanks will travel to the left in the direction indicated by the arrow 18, thus giving the workers time to lay the cleats and the sheets on the feed belts, so that they will then pass under the staplers and ultimately be discharged 20 at the left end of the machine.

A plurality of staplers 19 are provided on the machine, and operated by the main shaft 11, in any suitable or well known manner, thereby to staple the sheets to the cleats, and to staple the binding wires 20 in place as well. These staplers are carried by a frame composed of the cross bars 21 and 22 and the vertical links 23, which latter have their upper ends mounted to swing on the shaft 11, previously described, and the 30 upper ends of the links 23 are preferably interconnected by a bar 24 in the manner shown in Fig. 2 of the drawings. Thus, the shaft 11, by its rotation, actuates the staplers up and down, to form and drive the staples, in the ordinary 35 and well known manner.

However, in addition, these staplers have a swinging motion, back and forth, longitudinally of the machine, inasmuch as the bar 21 is connected by a link 25 with a crank arm 26 on the 40 rock shaft 27, which latter extends transversely of the machine and is mounted in bearings 28 and 29, the latter being mounted to slide in a plane horizontally and longitudinally of the machine. An eccentric pitman 30 connects the 45 shaft 11 with the crank arm 26, which latter is rigid with the crank arm 26, so that the rotation of the shaft serves also to rock the shaft 27 and thereby swing the stapler frame and the staplers thereon back and forth longitudinally of the 50 machine, whereby the staplers are made to travel a distance with the blanks during the actual insertion of the staples therein. By using continuus feed for the blanks, the speed of the machine is increased, over and above what it 55 would be with an intermittent feed, but with the blanks moving continuously, it is desirable to have the staplers move with them a distance during the actual insertion of the staples in the materials. As soon as the staples are inserted, then the staplers swing back to the opposite end of the arc which they traverse in the back and forth swinging movement.

In order that the staples may be positioned on the blanks, at predetermined desirable points 60 thereon, the shaft 27 is moved bodily back and forth in a plane horizontally, longitudinally of the machine, so that the arc of travel of the staplers is moved one way or the other, and this causes the staples to be driven at the desired 65 points in the work. The timing of the staple-driving is not changed, inasmuch as the rotation of the shaft 11 is not varied or controlled, but only the back and forth swinging movement of the staplers. The shifting of the shaft 27, one 70 way or the other, to automatically position the 75

staples on the blanks is accomplished automatically by means of a sprocket belt 32 which is driven by a chain belt 33 connected to the gearing 34, which latter is operated by the shaft 11, as clearly shown in Fig. 1 of the drawings. The 5 belt 32 is composed of blocks 35 having notches formed in their tops, and these notches may be relatively formed to provide a cam groove 36, as shown in Fig. 9 of the drawings. The blocks 23 and 29 have racks 37 that engage the pinions 38, which latter operate in a horizontal plane and are arranged to engage the rack bar 39 that extends transversely of the machine, and that is movable endwise, thereby to cause the shifting of the blocks 23 and 29 in a plane horizontally and longitudinally of the machine. In order to operate the bar 39 endwise, it is provided on its under side with a roller 40 that engages the cam groove 36, previously mentioned. The formation of the groove 36 will cause the roller 40 to 20 move laterally, and this will cause the rack bar 39 to move endwise, which will rotate the pinions 37 and 38, and thereby move the bearing blocks 23 and 29 in a plane horizontally and longitudinally of the machine, thus changing the position of the shaft 27, and thereby changing the position of the staplers. The latter will still have the same extent of swing or longitudinal stroke, but the arc of travel will be shifted one way or the other, in effect longitudinally of the machine, 30 and the consequence is that the staplers may be exactly vertical while inserting the staples as shown in Fig. 14, or may be swung in one direction as shown in Fig. 15, or may be inclined in the opposite direction as shown in Fig. 16 of the 35 drawings. This means that if the exact vertical position of the stapler, as shown in Fig. 14, is not calculated to insert the staple at the desired point in the materials, then the automatic control, provided by the cam groove 36, will swing 40 the stapler a little forward or a little backward, so that, instead of inserting the staple at the point 41 as shown in Fig. 14, it will be inserted at the point 42 as shown in Fig. 15, or at the point 43 as indicated in Fig. 16 of the drawings 45 which means that the point of insertion will be changed or varied longitudinally of the blank, in order that staples here and there may not be inserted at undesirable points. But this is done, as stated, without changing the timing of the insertion of the staples, inasmuch as the main driving of stapling shaft 11 is not controlled in any way, but is driven at a constant speed, which means that the timing is not advanced or retarded, but merely that the lower end of the 50 stapler is automatically swung either one way or the other to avoid the insertion of the staple at an undesirable point in the materials, but practically without changing the time or moment of driving.

In addition, the blocks 35 are provided with lugs 44 for engaging a rod 45, to move the latter endwise, thereby to rock the bell crank 46 and the link connections 47, 48 and 49 in a manner to oscillate or automatically adjust the shield or shroud 50 provided on the ratchet device by which the wire is fed to each stapler. These ratchet feed devices are well known, and well understood, and do not need any further description or illustration thereof, and it is common to 65 control these ratchet feed devices to prevent the feeding of wire to the staplers at moments when it is not desired to form and drive any staples. The shield or shroud 50 simply blocks the action 70 of the ratchet dog, so that the wire does not feed, 75

but in the present case this is done by the action of the same belt 32 that automatically controls the swinging stroke of the staplers. The lugs 44 are positioned on the blocks of the belt 32 in a manner to prevent action of the ratchet feed that supplies the wire to the staplers, at the proper time, so that, without stopping the operation of the staplers, no staples will be formed and driven at certain points on the work, as between the ends of adjacent blanks, or at other places, and thus the mechanical control by which the swinging motion of the staplers is automatically controlled is also employed for automatically controlling the ratchet devices by which the wire is fed to the staplers.

It will be understood that different sets of chains and blocks, similar to the chain 32 and the blocks 35, will be supplied and provided for blanks of different shapes and sizes, so that, by substituting one chain for another, the same machine can be used for short runs of blanks of different kinds. The link belt 32 and its blocks 35 may be said to provide a sort of self control for predetermining the positions of the staples on the blanks, in accordance with the character of the materials, and the shapes and sizes of the blanks, and in addition the lugs 44 will automatically prevent the forming and driving of staples in the spaces between the adjacent ends of blanks, or at other places, so that the entire automatic control is embodied in a link belt and its set of blocks and lugs, and there can be as many different belts as there are different shapes or sizes of blanks to be made on the machine. For some purposes, the link belt 32 might be necessarily longer than the one shown and described, or it might be shorter, and for this purpose it will be seen that a plate 51, with a slot 52, is provided, as a mounting for the sprockets on which the belt 32 is supported, so that this belt may be either longer or shorter, as the character of the blanks may require.

It will be understood that any suitable, known or desired, means can be employed for feeding the binding wires to the blanks, to be stapled in place thereon, in the usual and well known manner.

It is obvious, of course, that the invention is susceptible of definition in terms of process or method, as well as in terms of apparatus or machinery. As a process, it contemplates the establishment of a normal driving or insertion position, for the staples, relative to the machine itself, and the automatic moving or shifting of this position alternately forward and back, or in opposite directions, longitudinally of the direction of feed of the blanks, the motion of the latter being continuous. Also, it will be seen that the method involves a constant or non-variable timing for the driving or insertion of the staples, as the staple drivers have a predetermined timing, regardless of the shifting of the driving or insertion position. Also, practically, the continuous feeding motion of the blanks is preferably constant, and with that characteristic only the driving or insertion position of the staples is variable, and not fixed or constant, as both the timing of the driving and the timing of the feeding motion of the blanks remains constant. This results, of course, in an irregular spacing of the successive staples on the blanks, as the staples are not all driven in the same position relative to the machine itself. Absolute regularity of spacing of the successive staples, on the blanks, might obviously result in locating staples at undesired

points on the blanks, and hence the irregularity of spacing serves to avoid any such undesirable insertion of staples, and enables the process or method to serve effectively for the purpose of locating successive staples at predetermined points on the blanks, each of which points is suitable for the insertion of a staple. Of course, when the driving or insertion position is moved forward or back, the driving angle is necessarily changed, as shown, because of the swinging motion of the staplers about the overhead axis of the shaft 11 shown in the drawings. When staples are driven or inserted at the normal position, relatively to the machine itself, the driving or insertion direction is at right angles to the plane of the blanks, but when this driving or insertion position is changed, the driving or insertion direction becomes oblique to the blanks, as shown in the drawings.

Obviously, the process or method thus constituting the invention can be practiced by the use of machinery or apparatus of different kinds, and the control of the driving or insertion position of the staples, and the driving angle of the stapling mechanism (see the different driving angles indicated in Figs. 14, 15, and 16), relatively to the machine itself, can be accomplished by any suitable known or desired means, without departing from the spirit of the invention. However, the automatic control shown and described, by which the driving or insertion position of the staplers is moved either forward or back, or in opposite directions, longitudinally of the feed of the blanks, is illustrative of one form of such control, of a purely mechanical character.

It will be seen, therefore, that the rotation of the shaft 11, and the timing of the staple driving strokes, remains constant and regular and unchanged, during the variation of the stapling position, for said shaft continues to run at a predetermined constant speed during such variation. Also, the speed of travel of the feed belts 7 remains constant and unchanged, during such variation of the stapling position, as this variation in no way affects the predetermined speed of travel of said belts, and hence the stapling position, relative to the machine itself, is the only thing that is automatically changed or varied in order to insure insertion of the staples at predetermined regular or irregular points on the traveling blanks.

As indicated in Figs. 14, 15, and 16, the driving position of the stapling mechanism, or its driving angle, so to speak, changes or varies, longitudinally of the machine, in order to place the staples at predetermined points in the blanks. While the forward and back stroke of the stapling mechanism, over the blanks, is on the arc of a circle struck from the axis of the shaft 11 overhead, it is nevertheless true that the shifting of the stapling mechanism is substantially or in effect longitudinally of the machine, as it must be that in order to drive the staples either exactly on time, as indicated in Fig. 14, or a little ahead of time, so to speak, as indicated in Fig. 15, or a little behind, as indicated in Fig. 16 of the drawings, for in these figures the blanks are supposed to be traveling to the left. The back and forth stroke of the stapling mechanism, and the length of such stroke, does not change, as the terminals of said stroke remain a fixed distance apart, regardless of whether the stroke is moved ahead or backward, as the back and forth stroke is determined by the oscillation or rocking movement of the shaft 27, and this does not change, as the

excentrically operated pitman 30 has the same up and down stroke, practically, in any position of the stapling mechanism, when the latter is moved forward or back by the shifting of the 5 bearings 28 and 29 in which the shaft 27 is supported for rotation. Thus, in effect, the driving position, or the stapling position, is shifted longitudinally of the machine, as shown and described, but the swinging stroke of the stapling mechanism 10 remains constant, as the terminals of such stroke remain a fixed distance apart, notwithstanding that the stroke in its entirety is automatically moved one or the other, in the manner shown and described, to automatically locate the staples at predetermined points on the 15 blanks.

While only one use for the invention has been shown and described, which is the stapling of wirebound box blanks, it is obvious that the 20 invention can be used in different fields, for different purposes, for performing successive operations of any suitable or desired character, on any suitable or desired materials, by in effect shifting the point of operation longitudinally of 25 the direction of the feeding motion, and hence the invention can be used for other purposes without departing from the spirit of the invention.

The points of insertion of the staples are 30 changed, automatically, on the work, and it is this automatic shifting or adjusting of the points of insertion that results in either regular or irregular spacing of the staples, longitudinally of the machine, in the manner and for the purpose 35 explained, and while the said points of insertion are automatically changed, during the running of the machine, it is nevertheless true that the timing of the overhead stapling shaft 11 and the feeding movements of the feed belts 7 remain 40 constant.

Thus, as shown and described, the overhead transverse shaft 11 rotates continuously at a fixed or constant speed, and this is also true of the shaft 5 that causes the feeding motion of the 45 box blank materials, and the same is true of the shaft 27 that causes the stapling operation to move along with the materials, for each of these three shafts is driven or rotated continuously at a constant speed, notwithstanding that instrumentalities are provided for causing the stapling operations to be spaced either regularly or irregularly on the blanks or other materials.

What I claim as my invention is:

1. In a machine for stapling blanks, the combination of means for feeding the blank materials continuously longitudinally of the machine, stapling mechanism supported in position to operate upon the moving blank materials, devices for causing said mechanism to move back and forth longitudinally of the machine, so that each staple will be inserted while moving a distance with the materials, instrumentalities operable only while the machine is running for automatically controlling and changing the driving 55 position of said mechanism, longitudinally of the machine, to change the points of staple insertion longitudinally of the path of feeding motion of the work, while maintaining the length of said stroke of said mechanism, and power operated 60 means on the machine for operating said mechanism and devices and instrumentalities in predetermined sequence.

2. A structure as specified in claim 1, comprising means whereby the back and forth or longitudinal stroke of the stapling mechanism is on an arc 70

formed about a transverse overhead fixed axis, so that the direction of insertion of staples, because of said automatic control, may be vertical or more or less oblique.

3. A structure as specified in claim 1, said instrumentalities comprising a device providing a cam groove, with means engaging said cam groove to control and vary the driving position of said mechanism.

4. A structure as specified in claim 1, in combination with means for feeding a staple wire to said mechanism, and means on said instrumentalities for controlling the staple wire feed, to prevent the forming and driving of staples in the spaces between blanks or at other places. 15

5. A structure as specified in claim 1, said devices comprising a rock shaft for swinging said mechanism forward and back about a transverse overhead axis, and said instrumentalities being operative to shift said rock shaft longitudinally of the path of travel of the blank, thereby to change the driving position of said mechanism. 20

6. A structure as specified in claim 1, said power means being operative to maintain the operation of said mechanism constant and unvaried, notwithstanding the changing of the driving or insertion position of said mechanism by said instrumentalities. 25

7. A structure as specified in claim 1, said power means comprising an overhead transverse shaft supported to rotate about a fixed axis, for operating said stapling mechanism, said shaft being also connected to actuate said devices, in any changed driving position of the said mechanism. 30

8. A structure as specified in claim 1, said instrumentalities comprising a transverse rack bar, pinions mounted to rotate about vertical axes and engaging said rack bar, and parallel longitudinal racks engaging said pinions. 40

9. In a machine for making box blanks, by feeding the blanks continuously below a continuously operating and forward and back moving stapling mechanism, the combination of means for maintaining the timing of the operation of said mechanism constant, means for maintaining the length of forward and back stroke of the mechanism constant, means for maintaining the timing of said stroke constant, means for maintaining the blank feeding motion constant, and instrumentalities controlled automatically in the operation of the machine to change the points of insertion and therefore the spacing of the staples inserted in the blanks. 55

10. A structure as specified in claim 9, said instrumentalities having means operating automatically in the operation of the machine to shift the terminals of said forward and back stroke, while maintaining a fixed distance between said terminals, and while said timing remains constant. 60

11. A structure as specified in claim 9, in which said forward and back stroke is on the arc of a circle struck from a fixed overhead transverse axis, so that said arc is automatically moved forward or back, to change the spacing, while said timing remains constant, and while said axis remains in its fixed position. 65

12. A structure as specified in claim 9, in combination with automatic means operated by the operation of said instrumentalities to prevent attempted operation of said mechanism on any spaces in the materials. 70

13. A structure as specified in claim 1, in com- 75

bination with automatic means operated by the operation of said instrumentalities to prevent attempted operation of said mechanism on any spaces in the materials.

- 5 14. In a machine for performing successive operations on materials, the combination of means for feeding the materials, mechanism for perform the successive operations on the materials, at predetermined successive points thereon, and devices serving automatically to shift said mechanism longitudinally of the direction of said feeding motion, operative only during operation of said feeding means, thereby changing the operating position of said mechanism, and serving to 10 change the points of operation and therefore the spacing thereof on the materials.

15. A structure as specified in claim 14, said mechanism being also movable a distance with the materials while performing each operation 20 thereon, in any automatically adjusted position thereof.

25 16. A structure as specified in claim 14, said feeding motion being continuous, and remaining constant for different automatic adjustments of said mechanism, and the consequent different spacing of the points of operation on the materials.

30 17. A structure as specified in claim 14, in combination with automatic means operated by the operation of said machine to prevent attempted operation of said mechanism on any spaces in the materials.

35 18. A stapling machine in which the timing of the operation of all elements thereof is constant in speed but in which automatic means operable only when the machine is operating are provided to change the points of actual insertion and thereby the spacing between successive staples inserted in the work, while the machine 40 is running.

45 19. A structure as specified in claim 18, said machine being equipped to make wirebound box blanks, by continuous feed of the blanks, and said automatic means serving to change the points of insertion of the staples, to change the spacing of the staples on different blanks, or on different sections of the same blank.

20. A structure as specified in claim 18, in combination with separate means operated by the operation of said machine to prevent the attempted driving of staples in any spaces in the work.

5 21. A machine for feeding and performing successive operations on materials, in which means are provided whereby the timing of the feeding motion remains constant, but in which automatic means operable only when the machine is 10 operating are provided to change the points of operation and thereby the spacing thereof on said materials, and mechanical means to maintain the timing of the successive operations constant.

22. A machine equipped for performing successive stapling operations on moving materials, comprising a transverse overhead shaft that rotates continuously at a constant speed to perform said operations, a transverse shaft that rotates continuously at a constant speed to cause the 20 materials to move continuously at a constant speed, and instrumentalities wholly mechanical and operated by the operation of the machine and operable only when said shafts are rotating to automatically control the stapling operations 25 and thereby space the driven staples regularly or irregularly on the materials while maintaining constant the continuous feeding motion thereof.

30 23. A structure as specified in claim 22, comprising a transverse shaft and means to rotate said shaft continuously at a fixed or constant speed to in effect cause the stapling operation to move with the materials.

35 24. A structure as specified in claim 22, comprising a transverse shaft and means to rotate said shaft continuously at a fixed or constant speed to in effect cause the stapling operation to move with the materials, said instrumentalities comprising means for automatically shifting said 40 last mentioned shaft and thereby the stapling operation either forward or back longitudinally of the path of travel of the materials.

JULIUS J. MILLER. 45
